UNITED STATES PATENT OFFICE.

AMBERT M. MYERS, OF DAYTON, OHIO.

VAPOR-GENERATING DEVICE.

1,299,598.

Specification of Letters Patent.

Patented Apr. 8, 1919.

Application filed December 3, 1917. Serial No. 205,147.

To all whom it may concern:

Be it known that I, AMBERT M. MYERS, a citizen of the United States, residing at Dayton, in the county of Montgomery and State 5 of Ohio, have invented certain new and useful Improvements in Vapor-Generating Devices, of which the following is a specification.

This invention relates to new and useful 10 improvements in vapor generating devices.

The principal object of the invention is to provide a simple and effective generating device for supplying thoroughly diffused vapors for bath cabinets and other uses.

15 The preferred form of embodiment of my invention is illustrated in the accompanying drawings, of which Figure 1 is an elevational view, partly broken away, of the generating unit of my improved device. Fig. 2 is a top plan view of the base portion of the latter. Fig. 3 is a side view of the tray containing portion of the generating unit, being broken away to show some of the staggered chemical containing trays. Fig. 4 is a side 20 view, partly broken away, of the distributing unit of my improved device. Fig. 5 is an enlarged detail view of the condensing and trap portion of the distributing unit. And Fig. 6 is a bottom plan view of the trap portion 25 of the latter.

Throughout the specification and drawings, similar reference characters denote corresponding parts.

Referring to the accompanying drawings, 30 the numeral 1 designates a relatively square sanitary base containing a central rib 2 which supports an apertured gas burner 3 of preferably ring shape. This burner is supplied with gas or other combustible medium through a pipe 4. (See Figs. 1 and 2.)

Suitably supported upon the base 1 within its flanged portion 5, is the hollow lower end 35 of a cabinet 6. The latter contains a partition 7 which preferably slopes downwardly toward a central opening 8 which extends 40 upwardly through a tubular part 9. Above the latter the cabinet is formed to provide a space to receive a plurality of superimposed trays 10 which preferably rest upon brackets 11 secured to the walls of the cabinet. A slide 12 is provided to enable said 45 trays to be readily inserted and withdrawn. The cabinet has a sloping top 13 with preferably two chimney or vapor outlet por- 50 tions 14, 14.

Supported upon the base 1 above the

burner 3, is a drum 15 to which water or other liquid is admitted through a pipe 16. When the gas in the burner is ignited, steam vapors formed in the drum 15 will ascend 60 through openings provided therein, and the opening 8, to the tray-containing portion of the cabinet.

Each of the trays 10 contains a chemical, mineral or other substance whose beneficial 65 qualities it is desired to impart to the ascending vapors, for transference by them to the bath cabinet or other means designed to receive them. These trays are disposed in staggered relation, to permit the steam vapor 70 to circulate between them; that is, each tray is so placed within the cabinet that there is an opening left between one of its ends and the cabinet wall, for the vapor to ascend to the tray above, with sufficient space 75 left between the trays for the vapor to readily pass from one end opening to the other. As shown in Fig. 3, the lowermost tray has not been forced all the way in the cabinet, to leave sufficient space between its 80 inner end and the cabinet wall to permit the vapor to pass from the tube 9 to the tray above, the latter tray being in its innermost position to leave an opening between its outer end and the cabinet wall to admit the 85 vapor to the space above it, and so on to insure a thorough circulation of the vapor around the trays before it can leave the cabinet through the outlet portions 14, 14 of the latter. Thus it is possible for the vapors 90 to effectively receive from the trays, those properties which their contents are designed to impart. (See Figs. 1 and 3.)

The vapors are distributed by the unit now to be described. Referring to Fig. 4, 95 the numeral 17 designates a cabinet having a hollow upper vapor-receiving portion 18 provided with an opening 19 for communication, through a conduit not shown, with one of the vapor outlet portions 14 of the 100 cabinet 6. A partition 20 separates the upper cabinet portion 18 from its lower portion, the latter being adapted to receive a removable drawer-shaped pan 21.

For the purpose of permitting any condensation resulting from the vapors, to pass 105 to the pan 21, and at the same time preventing any vapors from entering it, the following trap construction is provided. Referring to Figs. 4, 5 and 6, the partition 20 has 110 a central opening 22 through which the condensation may pass to a cone shaped recep-

tacle 23 secured to the bottom face portion of said partition. In the top part of the receptacle 23 there are provided two oppositely disposed triangular slots 24 24 through 5 which the condensed vapor may pass to the pan 21. However, before it can enter these slots, the liquid must first pass through a tapering tubular member 25 secured to the partition 20, and extending into the conical 10 receptacle 23 a sufficient distance to bring its lower end below the triangular slots 24. Accordingly, the condensed vapor cannot escape to the pan 21 through the slots 24, which are outside the member 25, until it 15 has filled the bottom of the conical receptacle 23 above the level of the lower end of the hollow member 25. Therefore, there will be present in the lower end of the conical receptacle 23, sufficient liquid to form a 20 seal against any vapor which might otherwise pass out through the triangular slots 24. Nothing but the condensed vapor can descend to the pan 21, with the result that all the rest of it may be conducted through 25 the outlet tubes 26 26 in the top of the cabinet 17, to bath cabinets or other apparatus designed to receive it.

I do not wish to be limited to the details 30 of construction and arrangement herein shown and described, and any changes or modifications may be made therein within the scope of the subjoined claims.

Having described my invention, I claim:

35 1. In a device of the type described, the combination with a vapor generator, of a vapor distributing cabinet, a hollow vapor-

receiving compartment therein having a hole provided in its bottom portion, a condensation receiving receptacle below said hole, a hollow member whose upper end is 40 secured to the bottom of said compartment around said hole, and whose lower end extends well into said receptacle, said receptacle having outlet holes provided therein above the lower end of the hollow member 45 to discharge the condensation, and a vapor outlet in said compartment above the hole in the bottom of the latter.

2. In a device of the type described, the combination of a vapor generator, of a vapor 50 distributing cabinet, a hollow vapor-receiving compartment therein having a hole provided in its bottom portion, a conical receptacle below said hole to receive the condensed vapor, a tapering hollow member 55 whose upper enlarged end is secured to the bottom of said compartment around said hole, and whose lower end extends well into said receptacle, said conical receptacle being provided with a pair of triangular 60 slots above the lower end of said tapering member to discharge the condensation after the latter has filled the conical receptacle to a level above the mouth of the tapering member, and a vapor outlet in said compartment above the hole in the bottom of the latter.

In testimony whereof, I have hereunto set my hand this 30th day of November, 1917.

AMBERT M. MYERS.
